CLAIM

The ornamental design for a tripod, as shown and described.

DESCRIPTION

FIG. 1 is a perspective view of a tripod where a mobile phone is clamped on a clamping portion of the tripod showing my new design.

FIG. 2 is a perspective view of the tripod;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines in the drawings depict environment subject matter, specifically a mobile phone in FIG. 1, and portions of the tripod that form no part of the claimed design.
